UNITED STATES PATENT OFFICE.

HARRY G. TRAVER, OF BEAVER FALLS, PENNSYLVANIA.

AEROPLANE SWING.

Application filed February 7, 1920. Serial No. 356,881.

To all whom it may concern:

Be it known that I, HARRY G. TRAVER, a citizen of the United States, and resident of Beaver Falls, in the county of Beaver and State of Pennsylvania, have invented certain new and useful Improvements in Aeroplane Swings, of which the following is a specification.

This invention relates to amusement devices commonly termed as "Aeroplane swings," and it is the object of the invention to provide an amusement device of this character which is of a collapsible structure in which all of the parts are arranged and constructed to be releasably connected and disconnected, whereby the same may be quickly erected and taken or knocked down and the parts arranged in a collapsed and compact structure to be readily packed and transported.

In carrying out the invention I provide a collapsible supporting base and a tower to be supported thereby comprising nested or telescoping sections, together with means to move the tower to upright position on the base and to extend the sections when in upright position. A sectional shaft is adapted to be rotatably mounted in co-axial relation in the tower sections with arms supported from the inner and outer ends from the shaft to extend radially therefrom, with passenger carrying cars in imitation of aeroplanes or hydroplanes suspended from said arms, means being provided to rotate the shaft and thereby move the passenger carrying cars in a circular path.

A further object of the invention relates to a knock down passenger carrying car for aeroplane swings whereby the same may be collapsed into a compact structure to take up a minimum amount of space in transportation.

Another object of the invention relates to an imitation motor or engine to be utilized in connection with amusement devices of this character, including a revoluble propeller with means operable by the revolving of the propeller to make a noise in imitation of the exhaust of an internal combustion engine.

Other objects and advantages will herein-after appear.

In carrying out the invention I provide a base comprising a pair of girders connected in parallel and spaced relation by cross members, each girder having a pair of auxiliary girders connected and adapted to extend at

right angles thereto in line with the connecting member of the main girders and to be adjusted to extend parallel with and lie contiguous to the main girders. A collapsible tower consisting of telescoping or nested sections is arranged to be removably mounted upon the base, each tower section carrying a shaft section arranged to be coupled in axial alignment and operatively connected to driving means carried by the base. Arms are releasably supported at their inner and outer ends from the shaft to extend radially and in spaced relation therefrom and beyond the tower. Passenger carrying cars are removably connected to and suspended from the outer ends of the arms, said cars being constructed and conformed in shape to a hydroplane and are of a knock down structure whereby the cars may be collapsed and compactly folded to take up a minimum amount of space.

In the drawings accompanying and forming a part of this specification Figure 1 is a perspective view of an aeroplane swing illustrating an embodiment of my invention.

Figure 2 is a plan view of a base upon which to mount the swing supporting structure and showing the driving means for the swing.

Figure 3 is a front elevation of a portion of a pair of planes used in connection with the swing to show the manner of mounting a propeller in relation to an imitation engine mounted between said planes.

Figure 4 is a perspective view of a passenger carrying car in imitation of the fuselage of an aeroplane or hydroplane used in connection with the swing.

Figure 5 is a side elevation of the passenger carrying car shown in Figure 4.

Figure 6 is a perspective view of a collapsible side supporting frame of the passenger carrying car shown in Figures 4 and 5.

Figure 7 is a plan view and Figure 8 a side elevation, partly broken away, of means to suspend the passenger carrying cars from a rotatable support.

Figure 9 is an enlarged sectional plan view and Figure 10 is a perspective view of a portion of sections of a telescoping or adjustable tower for a rotatable shaft by means of which the passenger carrying cars are rotatably supported.

Figure 11 is a perspective view of a pair of shaft sections by which the cars are ro-

tatably supported and showing means to couple them together co-axially.

Figure 12 is a perspective view of a portion of the shaft supporting tower showing 5 the means to rotatably support the car supporting shaft centrally thereof.

Figure 13 is a side elevation of the tower supporting base.

Figure 14 is a side elevation showing the 10 means and manner of upending a telescoped or collapsed tower upon the base.

Figure 15 is a side elevation of the base and tower mounted thereon and showing the manner of extending the telescoping 15 sections of the tower.

Figure 16 is a side elevation of a portion of the car carrying shaft showing the means of suspending the cars from said shaft and the manner of moving said means to car 20 suspending position.

Figure 17 is a cross sectional view of the car frame; and

Figure 18 is a perspective view showing the car in folded or collapsed condition.

25 Similar characters of reference designate like parts throughout the different views of the drawings.

In the embodiment of the invention shown in the drawings the apparatus is supported upon a base consisting of a pair of girders 20, 21 of suitable construction and shown as built up of structural shapes and forms of steel, these girders being connected in spaced and parallel relation by 30 transverse members 22, 23 and may also be connected at their outer ends by transverse members 24, 25. Two pairs of auxiliary girders 26, 27 and 28, 29 are connected to the main girders to extend laterally therefrom in parallel and spaced relation in line with the transverse members 22, 23. These auxiliary girders are adapted to extend substantially at right angles to the main girders and be adjusted to extend 35 parallel with and lie contiguous to the main girders. For this purpose the auxiliary girders adjacent their inner ends are pivotally connected to the main girders as by pivot pins or bolts 30 passing through plates 45 31 and the auxiliary girders and by means of which plates the main girders 26, 27 and the transverse members 22, 23 are rigidly secured together, and which plates are adapted for a further purpose to be 50 hereinafter set forth. The auxiliary girders are secured in position to extend laterally from the main girders by bolts 32 engaging the plates and auxiliary girders. The outer ends of the auxiliary girders may also be 55 braced by transverse members 24', 25' releasably connected to said girders. By releasing the bolts 32 and removing the transverse members 24', 25' the auxiliary girders 60 may be swung on their pivotal connection 65 30 with the main girders to extend substan-

tially parallel with and lie contiguous to the main girders 20, 21 as shown in dotted lines in Figure 2.

A collapsible tower is adapted to be supported in upright or vertical position upon 70 the girder connecting plates 31 of the base. This tower comprises telescoping sections, or sections which are adapted to be nested, and shown in the present instance as two in number, 33 and 34, the one section as 34 75 being arranged to slidably engage in the section 33. These tower sections are of open frame construction of rectangular shape in cross section and built up of angle iron bars. Each tower section consists of four angle 80 iron corner pieces 37 fixed together in spaced relation at opposite ends and intermediate points by transversely extending truss bars 35 and by diagonally extending truss bars 36, these truss bars preferably 85 being of angle iron. The truss bars of the section 33 are fixed to the outer wall of the corner pieces of the tower section, while the truss bars of the section 34 are fixed to the inner wall of the cornerpieces, and the cross 90 sectional dimensions of the section 34 is slightly less than the section 33 whereby said section 34 may engage in the section 33 as clearly shown in Figures 9 and 10. To maintain the tower sections in spaced 95 relation and permit of the tower section 34 being readily moved into and out from the tower section 33 guide blocks 38 are fixed to the inner wall of the corner pieces of the tower sections 33 as by rivets 100 or bolts 39 the heads of which engage in countersinks in the blocks to be flush with or below the surface of the guide blocks, Figure 9.

The tower sections are adapted to be mounted and supported upon the base to extend upward therefrom. To readily upend the tower upon the base two of the end pieces of the lower tower section 33 are provided at their lower ends with hinge members 40 and cooperating hinge members are fixed to two of the girder connecting plates 31 as shown at 41, and the hinge members connected by removable pintles. To raise the tower sections they are placed relative to the base in a horizontal position to pass the hinge pintles through the hinge members when the tower sections are moved to upright position to be supported upon the base by the corner pieces of the lower section engaging the girder connecting plates 32. When the tower is hingedly or pivotally connected to the supporting base as stated the tower is in horizontal position and is upended or raised to vertical position upon the base by hoisting apparatus comprising a pair of cables 42 secured at one end to adjacent the top of the lower tower section and passed around sheaves carried at the top of gin poles 44 set substantially central- 105 110 115 120 125 130

ly of and at opposite sides of the base (Figure 14) and around sheaves 45 on the tower sections the opposite ends of the cables being connected to drums 46 revolvably carried by 5 the lower section and adapted to be rotated by cranks having a worm and worm wheel connection with the drums as shown at 47. It will be obvious that by operating the cranks to rotate the drums to wind the 10 cables thereon that the tower will be moved to upright position through its pivotal connection with the base to be supported upon the girder connecting plates 31. The tower sections are secured in upright position by 15 bolts passed through brackets fixed to the corner pieces of the lower tower section opposite to the corner pieces to which the hinge members are connected and the girder connecting plates 31 opposite to which the 20 hinge members are connected.

In this position of the tower sections the section 34 is nested within the section 33 and to extend or lift the tower sections 34 the cables 42 are passed around pulley blocks 25 48 connected to the top of the lower tower section and pulley blocks 49 connected to the lower end of the tower section 34 as clearly shown in Figure 15, the pulley blocks or sheaves 48, 49 being placed within the space 30 between the tower sections whereby the raising of the one tower section is greatly facilitated. By rotating the drums 46 to wind the cables thereon it will be obvious the inner tower section 34 will be raised or extended relative to the lower tower section. 35 By the arrangement described and the use of two hoists or drums the tower sections are readily moved to upright position and the inner tower section raised to extended 40 position. The tower sections are secured in extended position by bolts passing through the overlapping ends of the corner pieces of the tower sections as shown in Figure 1. To steady the tower braces 50^a are provided, 45 these braces being pivotally connected at their lower ends to the base girders and bolted to the corner pieces of the lower section at their upper ends whereby they may be released and folded to lie contiguous to the base girders.

Each of the tower sections is adapted to support a shaft section to rotate on a vertical axis with the one shaft section co-axial with the other shaft section and operatively 55 connected or coupled in such relation. The shaft section 50 in the tower section 34 is journaled in bearings 51 supported in fixed position by bars 52 extending substantially between opposite corners of the tower section 60 34 and arranged so that the bearings are co-axially of the tower. A shaft 53 is journaled in bearings similar to the bearings 51 in the tower section 33 and which are removably connected to bars similar to the bars 52. The shaft 50 has a coupling 54 fixed to the lower

end thereof adapted to co-operate with a coupling member 55 fixed to the upper end of the shaft 53 to operatively connect the two shafts. When the tower is to be dismantled the bearings for the shaft 53 are released and by slightly raising the shaft 50 the shaft 53 may be moved to one side of the tower section 33 thereby permitting the tower section 34 with the shaft 50 to be moved into the tower section 34.

The shaft 53 is rotatably supported at the lower end in a bearing 56 mounted upon supporting bars 57 extending diagonally between the corners of the main girders 20, 21 and the girder connecting members 22, 23. 70 The shafts are rotated through a bevel gear 58 on the shaft 53 meshing with a bevel pinion 59 fixed to a shaft 60 journaled in bearings supported by the bars 57 and the girder connecting member 23, a gear 61 on said shaft 60 meshing with a pinion 62 fixed to a shaft 63 also journaled in bearings mounted on the bars 57 and member 23, and driven from a suitable source of power by a belt (not shown) passing around a pulley 64 80 fixed on the shaft 63.

The shaft 50 is of such length as to project above the top of the tower section 34, as clearly shown in Figure 1. A head 60' has a hub portion 61' whereby it is fixed upon the projecting end of the shaft 50. The head 60' has an annular flange 62' at the peripheral portion extending in a plane parallel with the axis of the head, said flange having a series of pairs of recesses 63' cut through the flange, and the hub 61' has sockets or recesses 64' in line with the flange recesses 63'. A series of arms 65 to extend radially from the shaft 50, and comprising a pair of angle iron bars secured together by rivets 66, are adapted to be supported at their inner end by the shaft by engaging in the recesses 63' and sockets 64', the inner ends being guided into the sockets 64' and held against lateral movement by lugs 67 90 projecting up from the face of the head. In the present instance there are six of these arms although a greater or less number may be employed as desired. The outer ends of the arms are supported from the shaft by truss bars or cables 68 connected at one end to a disk 69 fixed to the upper extremity of the shaft 50 and the other ends connected to shackles 70 connected to pins passing through the outer ends of the arms 65. The arms are maintained in spaced relation one to the other by bars 71 extending between a pair of arms and connected at opposite ends to said arms. Passenger carrying cars (designated in a general way at C in Figure 1) are suspended from the extremities of the arms 65 by means of cables 72. These cables pass through shackles 73 at the ends of the arms and connected at opposite ends to the cars at opposite sides thereof. A car

115

120

125

130

C is supported by a pair of arms 65, one arm supporting the car adjacent the forward end and another adjacent the rear end, as clearly shown in Figure 1.

As stated it is an object of the invention to provide a passenger carrying car for amusement devices or swings of this character of a knock down structure, whereby the same may be readily collapsed to take up a minimum amount of space, and to construct the car to conform in outline to the body or fuselage of a hydroplane. For this purpose I provide a framework built up of angle iron, and comprising a pair of side supporting frames 74 and 75 constructed substantially as shown in Figure 6, the frame 75 having cut out portions to permit of entrance to and exit from the car as shown in Figure 4. The open spaces between the frame members are closed by sheet metal as shown.

The side supporting frames 74 and 75 are mounted in parallel and spaced relation by transverse bars 76, 77 and 78 pivotally connected at opposite ends to said frame members, and transverse bars 79 at opposite ends with diagonally extending transverse members 80 bolted at opposite ends to the members of the side frames. The frame is provided with a flooring consisting of matched boards 81 extending transversely of and supported between the bottom angle irons of the side frames and secured in matched relation by cleats 82. The bars 77 serve as seat supporting members, while the bars 76 serve as supports for the seat backs or back rests consisting of boards 83 hung from the bars 76 by cleats 84, the ends of the boards being adapted to engage upright members of the side supporting frames, as clearly shown in Figure 17. The bars 78 at the forward and rear ends extend beyond the sides and have perforations for the engagement of hooks connected to the car supporting cables 72, as shown at 85. One end of the seat back supporting bar 76 is offset as shown at 86 (Figure 17) to clear the top bar of the side supporting frame when the frame is collapsed or folded as shown in Figure 18, and to compensate for this offset of the bars the opposite end of the bars have a pin and slot connection with the opposite side frame, as shown at 87.

To make the car body conform to the shape of the body or fuselage of a hydroplane the side supporting frames 74, 75 are provided at the forward end with an end portion or member 88 constructed of an angle iron frame covered with sheet material and shaped to conform to the bow or nose of the conventional form of a hydroplane, and is releasably connected to the forward end of the frame members 74, 75 by rods 89 engaging in corresponding openings or holes in said frames and frame of the end mem-

ber 88. The rear end of the car is also constructed to conform to the stern or rear end of the fuselage of a hydroplane by releasably connecting thereto an end member 90 shaped to the conventional form of the stern of the fuselage of a hydroplane, and consisting of a framework built up of angle iron covered with sheet material, and releasably connected to the end of the side frames by rods 91 engaging openings in the side supporting frames and end member 90. A member 92 representative of a rudder is releasably connected to the rear of the stern member 90 by a rod 98 engaging openings in the supporting frame of said rudder and end member 90.

Supported in superposed relation to the car body are a pair of superposed planes 94 consisting of sheet material stretched over and between a frame and maintained in spaced relation by struts 95 and truss wires 96. These planes are supported from the car body by extending the center struts below the bottom plane, as shown at 95' and securing said extended struts to the frames of the car body as by threading nuts on the ends of said struts at opposite sides of the lower longitudinal members of the side supporting frames.

An imitation motor or engine of the radial extending cylinder type (designated in a general way by E) is supported between the planes at the forward ends and centrally between the lateral ends, as shown in Figures 3 and 4. This engine comprises a hexagonal frame 97 having sheet metal cylindrical members 98 fixed thereto, and is secured to the plane supporting frames by pins or bolts 99. A propeller 100 is rotatably supported axially of the cylinder supporting frame 97, said propeller being adapted to be revolved by the action of the air striking against the propeller blades as the car is moved through the air in the operation of the swing. As the propeller is revolved a toothed or ratchet wheel 101 rotates therewith, and as said wheel is rotated yielding means in the form of a spring detent 102 fixed to the cylinder supporting frame 97 is caused to ride over the teeth of the wheel making a clicking noise representative of or imitating the noise of the exhaust of an internal combustion engine.

To knock down the car the engine is removed by releasing the pins or bolts 99, when the planes are released from the car body by loosening or unscrewing the nuts from the extended ends 95' of the struts. The truss wires 96 are then released when the struts 95 may be removed and the planes folded together. The rudder and ends 90 and 88 are then released by removing the rods 93, 91 and 89. The truss bars 80 are then unbolted when the seat backs are moved up to right angles from the position shown

in Figure 17 when the car body may be collapsed or folded to the position shown in Figure 18.

To mount the car supporting arms 65 upon the projecting end of the shaft section 50 with the cars connected to said arms to be suspended therefrom hoisting means are provided, as shown in Figure 16, and consisting of a gin pole 103 arranged to engage the 10 shaft at the inner end above the head 60 and the outer end supported by a truss wire 104. A block and tackle 105 is connected to the outer end of the gin pole and to a connecting rivet 66 of the angle irons of the arms 65. 15 The truss members 68 are connected to the shaft head or disk 64 and the arm shackle 70 and the car supporting cables to the shackles 73 when the arms are raised to position so that the inner ends may be inserted 20 into the head recesses and sockets 63, 64.

To prevent the cars from swinging inward and colliding with the tower a bumper or guard rail is provided consisting of a hexagonal frame 107 of angle iron which is 25 suspended by cables 108 from the car carrying arms 65 to engage between the cars and the tower.

The cars are suspended from the arms 65 so that in the normal idle position of the 30 cars the bottom will clear the top of the base girders and permit loading and unloading of the cars from the ground. To facilitate the loading and unloading of the cars a loading platform 109 extends around the 35 base of the tower and is supported upon the base girders.

Having thus described my invention, I claim:

1. In an aeroplane swing a collapsible 40 tower comprising telescoping sections; a sectional shaft one shaft section adapted to be rotatably mounted in each tower section and the shaft sections coupled co-axially; a head having a hub portion whereby it is fixed to the shaft and having radially extending recesses and sockets therein; and car carrying arms removably supported at one end in the head recesses and sockets and their outer ends trussed from the shaft.

2. In an aeroplane swing a collapsible 45 tower comprising telescoping sections; a sectional shaft rotatably mounted and co-axially coupled in the tower sections; a head having a hub portion whereby said head is fixed to the shaft, said head having an annular flange at the peripheral portion extending parallel with the axis of the head, radial slots in said flange, and sockets in the hub in line with the recesses; and car carrying arms removably engaging and supported at their inner ends in the hub recesses and sockets and their outer ends trussed from the shaft.

3. In a collapsible aeroplane swing a 50 knock down base; a tower removably mount-

ed on the base comprising telescopic and nested sections adapted to be extended and secured in extended position; a sectional shaft rotatably mounted in each tower section and adapted to be co-axially coupled 70 when the tower sections are extended; arms removably supported at their inner and outer ends from the upper shaft section to extend radially therefrom; cars suspended from said arms; and means to rotate the 75 shaft sections for the purpose specified.

4. In an aeroplane swing a tower; a shaft 80 rotatably mounted in said tower with the end projecting above the tower; arms supported at their inner and outer ends to extend radially from the projecting end of the shaft; cars suspended from the extremities of said arms; and a guard suspended from the arms to extend around the tower between the tower and cars for the purpose 85 specified.

5. In an aeroplane swing, a tower comprising sections releasably supported in superposed relation; means for releasably securing the tower in upright position; a shaft 90 rotatably mounted in the tower sections; a hub fixed to said shaft arranged with sockets and recesses extending radially from said sockets; and passenger car carrying arms mounted in said hub sockets and recesses for the purpose specified. 95

6. In an aeroplane swing a tower; a shaft 100 rotatably mounted in said tower; arms carried by said shaft to extend radially therefrom beyond the tower; passenger carrying cars suspended from said arms outside of the tower; and a guard rail interposed between the tower and cars and participating in the movement of the cars for the purpose 105 specified.

7. In an aeroplane swing, a base, a tower 110 comprising sections releasably supported upon the base in superposed relation; means for mounting and securing the tower in upright position; a shaft rotatably mounted in the tower; arms carried by said shaft to extend radially therefrom; passenger carrying cars suspended from the arms outside and in spaced relation to the tower; and a guard rail suspended from the arms and interposed between the tower and cars for the purpose specified. 115

8. In an aeroplane swing, the combination of a tower; passenger carrying cars carried by said tower to revolve in a horizontal plane; and a guard rail suspended from the car supports to encircle the tower and interposed between the tower and cars to prevent the latter from colliding with the tower during the revolving thereof. 120

9. In an aeroplane swing, the combination of a collapsible tower; means to releasably support the tower in upright position; passenger carrying cars carried by said tower to revolve in a horizontal plane; and means 125

interposed between the tower and cars and revoluble with the cars to prevent the cars from colliding with the tower for the purpose specified.

5. 10. In an aeroplane swing, the combination of a tower; passenger carrying cars carried by said tower to revolve in a horizontal plane; and a guard rail encircling the tower and revoluble with the cars to prevent the latter from colliding with the tower during the revolving movement thereof.
10. 11. In an apparatus of the character described, a base; a tower detachably secured thereon and comprising an upper and lower half; said upper half being telescopic within the lower half; detachable means for securing the upper half of the tower when in raised position, to said lower half; braces connecting the lower half of said tower and said base, said braces being hinged and permanently secured to one of the parts and detachably secured to the other; means for raising and lowering said upper half; a sectional shaft detachably supported by and centrally of said tower and means for rotating said shaft.
20. 25.

Signed at Beaver Falls, in the county of Beaver and State of Pennsylvania, this thirty-first day of December A. D. 1919.

HARRY G. TRAVER.
